UNITED STATES PATENT OFFICE

93,703

DESIGN FOR AN INFLATABLE MATTRESS

Cyril Renton Coomber, London, England, assignor
to P. B. Cow and Company Limited, London,
England

Application July 31, 1934, Serial No. 52,760
In Great Britain May 4, 1934

Term of patent 7 years

To whom it may concern:

Be it known that I, CYRIL RENTON COOMBER, a subject of the King of Great Britain, residing at Factory Square, Streatham Common, London, England, have invented a new, original, and ornamental Design for an Inflatable Mattress, of which the following is a specification, reference being had to the accompanying drawing, forming part thereof:—

The drawing shows a perspective view of the inflatable mattress, illustrating my design.

I claim:

The ornamental design for an inflatable mattress substantially as shown.

CYRIL RENTON COOMBER.
